Primary Examiner — Elizabeth J Oswecki(74) *Attorney, Agent, or Firm* — Rumit Ranjit Kanakia(57) **CLAIM**

The ornamental design for a halloween decoration, as shown and described.

DESCRIPTION

FIG. 1 is a perspective view of a halloween decoration showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged portion view taken from encircled portion labeled, "FIG. 8," in FIG. 1;

FIG. 9 is an enlarged portion view taken from encircled portion labeled, "FIG. 9," in FIG. 1; and,

FIG. 10 is an enlarged portion view taken from encircled portion labeled, "FIG. 10," in FIG. 1.

The broken lines in the figures are for the purposes of illustrating portions of the halloween decoration, which form no part of the claimed design.

1 Claim, 10 Drawing Sheets(56)
